UNITED STATES PATENT OFFICE.

ALFRED M. LANE, OF ST. LOUIS, MISSOURI, ASSIGNOR TO MONARCH METAL PRODUCTS COMPANY, OF ST. LOUIS, MISSOURI, A CORPORATION OF MISSOURI.

METAL WEATHER STRIP.

Application filed May 28, 1923. Serial No. 641,931.

To all whom it may concern:

Be it known that I, ALFRED M. LANE, a citizen of the United States, and a resident of the city of St. Louis and State of Missouri, have invented a new and useful Improvement in Metal Weather Strips, of which the following is a specification.

This invention relates to metal weather stripping particularly adapted for windows.

The present invention has for its principal objects to provide a cheap, simple, efficient device for weatherproofing a sliding window and which will not interfere with the operation of the sashes, to provide for the installation of said device without alteration of the sash or frame, to reduce the cost of manufacture, and to facilitate assembly. The invention consists principally in the hereinafter described weather strip and in the parts and in the arrangements and combinations of parts hereinafter described and claimed.

In the accompanying drawing, wherein like reference numerals refer to like parts wherever they occur,

Fig. 1 is a fragmentary horizontal cross-section through one side of a window casing and the adjacent portion of a lower sash provided with a weather strip embodying my invention; and

Fig. 2 is a horizontal cross-section similar to Fig. 1 showing a weather strip of modified form.

Referring to Figs. 1 and 2 of the drawing, a portion of the casing or jamb member 3 of an ordinary window frame is shown as arranged for a sliding sash 4, the walls of the vertical slideway for the sash being formed by a parting strip or bead 5 and a stop member or molding 6.

The weather strip illustrated in Fig. 1 of the accompanying drawing comprises a relatively flexible jamb or frame strip or member 7 and a relatively rigid sash strip 8, said strips being mounted vertically on the jamb 3 and on the sash 4, respectively. The jamb strip 7 is secured along one marginal portion to the jamb 3 of the window frame, as at 9, preferably under the stop member or molding 6. The jamb strip 7 extends between the opposing surfaces of the jamb 3 and sash 4 and has its opposite free marginal portion longitudinally doubled to form a double thickness of metal which is bent across the outer vertical cor-

ner of the sash and formed into a hook-shaped flange 10. This hook-shaped free marginal portion 10 of the jamb strip 7 is located opposite the front face of the sash; and the adjacent corner of the parting bead 5 is rabbeted to make room for said hook portion of said jamb strip. On the side opposite to the hook flange 10 the jamb strip 7 has its extreme free marginal portion bent substantially at right angles to its body portion to provide a flange 11. This flange portion 11 works loosely in a vertical groove 12 provided therefor between the back face of the parting strip 5 and the adjacent wall of the groove provided therefor in the jamb member 3 of the window frame.

The cooperating sash strip member 8 is relatively rigid and is secured along one margin to the outer face of the sash 4, as at 13, preferably clear of the adjacent edge 75 of the parting strip or bead 5. The opposite free marginal portion of this rigid sash strip or member 8 is bent outwardly at right angles to the body portion of the strip, preferably flush with the end face of the sash, 80 and is then rebent parallel with the body portion to form a hook-shaped flange 14. The hook-shaped flange portion 14 of the rigid sash strip 8 interlocks with the hook-shaped flange portion 10 of the resilient 85 jamb strip 7 and has a loose sliding fit therein. The rebent marginal portion of the sash strip 8 is spaced far enough from the body portion thereof to accommodate the rebent marginal portion of the jamb strip 90 7; and likewise, the rebent marginal portion of the jamb strip is spaced far enough from the adjacent portions thereof to accommodate the rebent marginal portion of the 95 sash strip.

In the construction illustrated in Fig. 2, the doubled free marginal portion of the relatively flexible or resilient jamb strip 7^a is bent inwardly across the outer corner of the sash and is thence rebent parallel with the inwardly bent portion to form a hook flange 10^a. The extreme marginal portion of the jamb strip is extended far enough beyond the body portion thereof to form a flange 11^a which works loosely in the groove 105 12 provided therefor in the window frame or jamb 3.

The free marginal portion of the rigid sash strip 8^a is offset outwardly from its body portion far enough to accommodate the 110

hook flange 10^a of the flexible jamb strip, and is then rebent parallel with the offset portion but spaced therefrom far enough to enter the opening in the rebent two-ply hook flange 10^a of the flexible jamb strip 7^a. The loosely interlocked hook flanges of the two strips form a sliding, floating weatherproof joint that permits free sliding movement of the sash; and it also accommodates slight 10 transverse and tilting movement of the sash relative to the frame.

It is noted that by the arrangements described, the interlocked hook portions of the two strips are effective in preventing drafts 15 and keeping out dust and water. Another important advantage is that the device is not only waterproof under normal conditions but that it remains waterproof against hard rains and driving wind. Under such conditions, the force of the wind against the sash tends to force the two cooperating strips into closer engagement with each other and thus prevent storm water from being forced through the crack between the sash and the 25 frame.

It is also noted that the jamb strip, owing to its resiliency, prevents binding and maintains a weatherproof connection between the two strips in the event that the sash swells, 30 shrinks or is loosely fitted in the window frame. Another advantage of my invention is the facility with which it may be applied. In both cases the two members forming the weather strip may be applied directly without any alteration of the sash. In addition to this, my invention is very easy to make 35 and any broken or worn part may be quickly and easily replaced.

Obviously, the invention is not limited to 40 use with the window construction shown and described.

What I claim is:

1. The combination of a frame and a closure therefor, of a member secured to 45 said frame adjacent to one corner of said closure, and a member secured to said closure adjacent to the opposite corner thereof, said members having loosely interlocked portions located beyond said opposite corner of 50 said closure.

2. The combination of a frame and a closure slidably mounted therein, of a mem-

ber secured to said frame adjacent to one side of said closure and having a free marginal portion extending beyond the opposite 55 side of the closure and provided with a hook flange, and a member secured to said opposite side of said closure and provided with an outwardly offset hook flange adapted to loosely interlock with the hook flange 60 of said first mentioned member beyond said opposite side of said closure.

3. The combination of a frame and a closure therefor, of a member located between the frame and the end face of the 65 closure and secured to said frame adjacent to one corner of said closure and having a rebent free marginal portion extending beyond the opposite corner of said closure, and a member secured to the side of said 70 closure adjacent to said last mentioned corner and having a rebent free marginal portion offset outwardly from said side of said closure and slidably engaging the rebent free marginal portion of said frame 75 member.

4. The combination of a frame and a closure therefor, of a metal weather strip comprising a flexible member and a rigid member mounted on said frame and said 80 closure, respectively, said flexible member having a single-ply body portion located between the frame and the end face of the closure and secured to said frame adjacent to one corner of said closure and having a 85 double-ply free marginal portion extending beyond the opposite corner of said closure and loosely interlocking with said rigid member.

5. The combination of a window frame 90 and a sash therefor, of a relatively flexible member secured along one margin to said frame and having a longitudinally doubled free marginal portion that projects beyond the side of said closure and is formed into a 95 hook flange, and a relatively rigid member secured to said side of said closure and provided with an outwardly offset hook flange portion slidably interlocking with the hook flange portion of said flexible member. 100

Signed at St. Louis, Missouri, this 16th day of May, 1928.

ALFRED M. LANE.
